UNITED STATES PATENT OFFICE.

FRANK H. ADAMS, OF CLEVELAND, OHIO.

REPEATING AND STOPPING ATTACHMENT FOR PHONOGRAFS.

1,317,258.

Specification of Letters Patent. Patented Sept. 30, 1919.

Application filed April 30, 1915. Serial No. 24,843.

To all whom it may concern:

Be it known that I, FRANK H. ADAMS, a citizen of the United States, residing at Cleveland, in the county of Cuyahoga and State of Ohio, have invented a certain new and useful Improvement in Repeating and stopping Attachments for Phonographs, of which the following is a full, clear, and exact description.

10 This invention relates to a repeating and stopping attachment for phonographs and is an improvement over the constructions disclosed in my prior applications No. 859,271, filed August 31, 1914, and No. 3,674 filed 15 January 22, 1915.

In each of the prior applications above referred to there is disclosed a repeating and stopping attachment including a pivoted track arm which extends horizontally over the disk record, and provided at its inner end with a dog, which, when the playing of the record is completed, is automatically shifted into engagement first with an elevating groove and then with a lowering groove provided in an elevating and lowering spindle extending upwardly above the record and attached to the driving spindle of the record. When the track arm is elevated, that is, when the inner end of the arm is elevated so as to incline the track arm, the needle is lifted from the record and the sound box and tone arm are restored to starting position, whereupon the playing of the record is repeated.

35 In the second named application, a construction is shown wherein the playing of the record is automatically repeated once or a predetermined number of times, after which the brake is automatically applied 40 to stop the instrument.

In carrying out the inventions constituting the subject matter of the two above named applications, I have utilized various devices for timing the engagement of the dog or other operative device at the inner end of the track arm with the elevating groove of the elevating and lowering spindle. In one arrangement which I have used, a member projecting from the sound box, 45 (either the needle or some other part such as a downwardly projecting arm) is caused to engage in a spiral groove cut or otherwise provided in the record at some point at or adjacent the end of the tone groove, 50 causing said member to engage and shift a part projecting laterally from the dog

whereupon the latter is moved into engagement with the elevating groove of the spindle. In another construction or arrangement which I have used, a trip finger or an arm which projects laterally from the inner part of the track arm is designed to be set to a definite or certain position by means of a scale and movable indicator, this arm or trip device being adapted to be engaged by some part projecting downwardly from the sound box, and when engaged causing the dog to be shifted into engagement with the elevating groove. Neither of the above arrangements or constructions is wholly satisfactory, because the first arrangement referred to requires that special grooves be cut into the records to adapt them for the instrument to which the repeating attachment is applied, and the second arrangement referred to requires that the records be numbered or otherwise provided with data which indicates in some manner the position on the scale to which the pointer must be set to cause the trip finger to be engaged and shifted at the proper time.

One of the objects of the present invention is to provide a suitable trip device which times the elevating of the track arm, and which may be adjusted or set to any desired position with reference to the end of the tone groove without requiring the use of any special marks, grooves, or indicating data on the records, and without requiring any previous testing or trying of the records to determine the point to which the trip should be set. Additionally, the invention aims to provide a trip device which is sensitive and is required to be moved only a slight distance to cause the release of the dog on the track arm.

A further object is to provide on the repeating attachment, and especially in connection with that part which controls the number of times the playing of a record is to be repeated, an electrical circuit controlling device which may be utilized in an electric motor driven instrument, to cause the stopping of the motor at the desired time.

The above and other objects are accomplished by my invention, which may be briefly summarized as consisting in certain novel details of construction and combinations and arrangements of parts which will be described in the specification and set forth in the appended claims.

In the accompanying sheets of drawings,

Figure 1 is a top plan view of a part of a disk phonograph equipped with my invention; Fig. 2 is a sectional view through the same; Fig. 3 is an enlarged sectional view 5 through a portion of the instrument showing particularly the repeating and stopping mechanism; Fig. 4 is a bottom view of the track arm and of the parts carried thereby; Fig. 5 is a plan view of what may be termed 10 the director arm and certain parts carried thereby; Fig. 6 is a sectional view substantially along the line 6—6 of Fig. 5; Fig. 7 is a vertical sectional view substantially along the line 7—7 of Fig. 5; Fig. 8 is a 15 partial longitudinal sectional view substantially along the line 8—8 of Fig. 1; Fig. 9 is a transverse sectional view substantially along the line 9—9 of Fig. 1; and Fig. 10 is a similar view substantially along the 20 line 10—10 of Fig. 1.

The attachment may be applied to a phonograph of the disk type without making any changes in the construction of the instrument, and in the drawings I have 25 shown the attachment applied to a phonograph of a well known type including a cabinet 10; a turntable 11, on which is adapted to be placed a disk record 12, and which is adapted to be driven by a vertical 30 driving spindle 13 projecting upwardly through a horizontal partition or base 14 located just beneath the turntable and spaced slightly therefrom. The instrument includes also a tone arm 15, which is movable about 35 a vertical axis, a U-tube 16 movable about a horizontal axis, and a sound box 17 carrying a sound producing needle 18.

Before describing the improvements in which the present invention is directly involved, I shall describe briefly those parts of 40 the attachment which are shown and described in the prior applications, and for a complete understanding and full description of the same reference is had to the prior 45 applications.

The attachment here shown, like the attachments constituting the subject matter of the aforementioned applications, includes a track arm 19, which is pivoted on a horizontal axis at the side of the turntable and disk record, and extends over the turntable and record toward the vertical driving spindle 13. This track arm 19 is provided on 50 its inner end with a pivoted dog 20 having a pair of spaced oppositely disposed fingers 55 21 and 22 adapted to successively engage the elevating and lowering grooves 23 and 24 of a spindle 25 adapted to be removably attached to the upper end of the driving spindle 13.

A trip device, which will be further referred to presently, and which constitutes one of the main features of the present invention, is adapted to time the engagement of the 65 elevating finger of the dog 20 with the ele-

vating groove to cause the inner end of the track arm to be elevated, and the track arm as a whole to be inclined downwardly from its inner end to its outer end. When the track arm is thus inclined it engages a roller 70 75 26 carried by an arm secured to the sound box or U-tube 16, and lifts the needle clear of the record, causing the tone arm and sound box to be restored to starting position by riding down the inclined track arm.

The movement of the tone arm and sound box just described is limited by a stop device 27, consisting of a lever pivoted on the under side and adjacent the outer end of track arm 19. This lever is provided with 80 two shoulders or abutments, either of which may be moved into the path of the needle or other appropriate part carried by the sound box so as to adapt the attachment to either a standard 10-inch or a standard 12- 85 inch record.

When the dog 20 reaches the upper end of the elevating groove in the spindle 25 with one of the fingers of the dog engaging said groove, a cam at the upper end of the spindle rocks the dog causing the lowering finger to be shifted into the lowering groove and the elevating finger of the dog to be shifted out of the elevating groove, whereupon the track arm is restored to normal 95 position and the needle is lowered into the tone groove and the playing of the record is repeated.

In the second of the above mentioned applications, there is disclosed a construction 100 wherein the playing may be repeated a predetermined number of times, after which the instrument is stopped. The construction shown in said application includes a director arm 30 which lies on the partition or base 14 beneath the turntable, and at its inner end is provided with an opening through which the driving spindle 13 extends. This director arm 30 is provided at its outer end, just beyond the turntable, with upwardly 110 projecting flange portions to which the track arm 19 is hinged at 31. A brake lever 32 which is hinged at 33 to the rear flange or wall 34 of the director arm is provided with a brake device or shoe 35 and has its outer 115 end projecting through an opening 36 in the front or near flange or wall 37 of the director arm. This wall 37 is provided with a series of shoulders, three being here shown designated *a*, *b*, *c*, and beneath these shoulders a notch 41, and below this notch a shoulder 42. The track arm 19 is provided with a downwardly extending flange or bracket 43 just inside the wall 37, having a series of shoulders corresponding in number 120 125 to the shoulders provided in the wall 37, these shoulders which are designated *d*, *e*, *f*, being below and displaced laterally outward slightly with respect to the corresponding shoulders *a*, *b*, and *c*. The lever 32 which is 130

pressed inwardly toward the shoulders by a spring 45, and the shoulders provided in the wall 37 and bracket 43 constitute an escapement device, which enables the attachment to be set to repeat indefinitely or a predetermined number of times, the number of repeats being limited by the number of shoulders provided in the parts 37 and 43.

By providing the director arm 30 which 10 extends beneath the turntable to the spindle 13, and by providing at the inner end of this arm an opening through which the spindle extends, the attaching of the repeating and stopping mechanism to a phonograph is 15 facilitated because the director arm with the opening through which the spindle extends positions the mechanism the proper distance from the turntable and from the elevating and lowering grooved spindle. 20 The combination of the track arm with the so-called director arm while shown in one of my prior applications, viz., Serial No. 3,674, is claimed herein.

The operation of the construction just 25 described is as follows:—If it is desired that the instrument repeat the playing of a record indefinitely, the lever 32 is placed against the shoulder 42 at the bottom of the opening 36. If it is desired that the record be played three times, the brake lever 32 will be drawn back and moved up into engagement with the shoulder *d*, as shown in Fig. 3. When the record has been played once, the track arm will be raised, and as 30 it is elevated the brake lever will be carried up into contact with the flat surface of the wall 37 overlying the shoulder *d* by which it will be pushed out of engagement with the shoulder *d* and will be allowed to 35 move into engagement with the shoulder *a*. Then, when the track arm descends, the bracket 43 will engage the lever and push it down out of contact with the shoulder *a* and allow it to move into engagement with 40 the shoulder *e*. These operations will be repeated with each up and down movement of the track arm, the brake lever passing progressively from shoulder *e* to shoulder *b*, from shoulder *b* to shoulder *f*, from shoulder *f* to shoulder *c*, and thence into the notch 45 41 which causes the brake to be applied. If it is desired that the record be played twice, the brake lever will be initially placed in contact with shoulder *e*, and if it is to be 50 played only once, it will be initially placed in contact with shoulder *f*.

Having described the general construction of the attachment, and particularly those parts shown in my prior applications, 55 reference is now had to the improved mechanism for causing engagement between the dog at the inner end of the track arm with the grooves of the elevating and lowering spindle 25. It will be observed particularly 60 by reference to Fig. 4, that the track arm

is provided on its lower side and near the inner end thereof with a latch in the form of a lever 50 pivoted at 51 to the track arm near one edge thereof. This lever which is in the form of a bell crank has one of its 70 arms projecting toward the pivoted dog 20, and is provided at its end with a hook or nose 52 which is adapted to engage a shoulder 53 provided on the dog. A coil spring 75 54 is connected at one end to a pin 55 on the lever 50, and at its other end is connected to the dog at such a point that when the nose 52 is disengaged from the shoulder 53, the spring turns or rocks the dog slightly, a 80 stop shoulder 56 limiting the rocking movement to a predetermined amount. The spring functions also to hold the nose 52 in engagement with the shoulder with the dog and track arm in the relative positions shown in Fig. 4. One end or arm of this 85 lever 50 projects along the track arm near one edge thereof, and alongside said arm is a slot 57 cut in the track arm. Mounted in this slot is a screw or stud 58, which, together with a nut 59, washer 60, and small coil spring 60^a in the nut holds with frictional engagement against the lower side of the track arm a trip finger 61 which projects laterally from the track arm and is in the path of the travel of some part projecting downwardly from the sound box, this part in this instance being the needle 18. The trip finger 61 is provided at its inner end with a camming surface or shoulder 62 which lies alongside and adjacent to the 90 arm of lever 50. By the construction shown and above described, this trip finger 61 is held frictionally to the track arm and may be adjusted lengthwise of the slot 57. The trip finger is provided at its outer end with a pointer 61^a which is designed to be set by the operator to some position with reference to the end of the tone groove of the record so that when the needle reaches a corresponding point in the record groove it will 95 shift the finger 61, causing the camming part 62 thereof to rock the lever 50 and release the dog 20. This will cause one finger of the dog to enter the elevating groove in the member 25, whereupon the track arm 100 will be elevated and the tone arm and parts carried thereby restored to starting position, as described in the prior applications. The pointer of the trip finger 61 can be set to cause the elevation of the track arm when 105 the needle reaches any desired point. For example, the pointer can be set to cause the track arm to be elevated when the needle is at the end of the tone groove, that is, the sound producing part of the groove, or it 110 can be set to a position such that the track arm will be elevated a predetermined time after the needle has passed the end of the tone groove, or before it reaches the end. This trip finger will be set to the desired 115 120 125 130

position just before the playing of the record is started, and, as before stated, with this device there is not required any previous marking or numbering of the records to determine the point to which the trip device should be set, and inasmuch as this finger is shifted by the needle or other part projecting downward, due to the regular inward travel of the needle toward the center 10 of the record as it follows the spiral tone groove, no special track groove is required to be put into the record to cause the shifting of the trip finger. It may be said further that the trip finger is required to 15 be shifted only a very slight amount to cause the release of the dog 20 from the lever 50. This renders the device sensitive and results in the elevation of the track arm very shortly after the needle engages the edge 20 of the trip finger.

When the dog is rocked by the small cam at the top of the elevating groove, causing one of the fingers of the dog to be removed from the elevating groove, and the opposite 25 finger to be inserted in the lowering groove, the dog and lever are automatically latched, thus restoring these parts to the relative positions which they occupied prior to the elevation of the track arm.

30 As an additional feature of the present invention, I have provided in connection with the brake lever 32 a circuit breaker which is designed to be employed in connection with an instrument driven by an electric motor, and is utilized for the purpose of opening the motor circuit to stop the motor when the playing of the record is to be stopped. I have not shown the motor nor the entire motor circuit, as it is believed that 35 such a description or additional illustration is unnecessary, and that the invention will be understood without the same. This circuit breaker is formed in part by the trip lever 32 and in part by a spring pressed terminal 65 which is mounted in an insulating bushing 66 supported on the outer upstanding wall or flange of the director arm 30. One conductor 67 of the electric circuit passes through an insulating bushing 68 in 40 the base of the director arm, and is connected to this terminal 65. The other conductor 69 passes through a similar insulating bushing and is grounded on the director arm. The inner face of the terminal 65 is 45 somewhat enlarged, and will be pressed by the spring 70 against the adjacent edge of the brake lever 32, as long as the latter is in engagement with any of the shoulders *a*, *b*, *c*, or *d*, *e*, *f*. This maintains the circuit of 50 the driving motor closed from the starting of the playing of the record, regardless of how many times the playing of the record is repeated, until the brake lever is moved by the spring 45 into the notch 41 after the record 55 has been played a predetermined or se-

lected number of times, when the brake lever moves out of contact with the terminal 65, the motor circuit is broken and the rotation of the turntable and disk record stop. With the construction here shown, simultaneously with the stopping of the motor, the brake is applied, as previously described, but it is not absolutely necessary that the brake be applied when the motor circuit is opened although I prefer both to apply the 75 brake and stop the motor simultaneously. It will be understood that the small spring behind the terminal 65 keeps the brush firmly in contact with the brake lever 32 while the same is shifted back and forth or from 80 shoulder to shoulder by the raising and lowering of the track arm, and it is to be understood that the brake lever does not move out of engagement with the terminal until the brake lever is automatically or manually 85 placed in the slot 41. The head or end of the terminal 65 is sufficiently long that it will be engaged by the lever 32 when the latter is engaging the shoulder 42.

The word "phonograph" as used in the 90 specification and claims is not intended to limit this application to a machine sold under the trade name "phonograph" but includes any sound reproducing or so-called talking machine utilizing a disk record or 95 of the general type herein shown and described.

Having thus described my invention, what I claim is:—

1. In a repeating and stopping attachment 100 for sound reproducing machines having means for rotating a disk record and having a tone arm, a track arm adapted to extend over a record supported on the rotating means, rotatable means for lifting the track arm when one end of the latter is moved into operative engagement with respect to the said rotating means, and means for timing such engagement comprising a device carried by the track arm and adapted to be set or 110 placed relative to said track arm so that the lifting of the track arm will take place substantially when the record has been reproduced to a point on the record which is directly indicated by such means. 115

2. In a repeating attachment for sound reproducing machines having means for rotating a disk record, a tone arm and a sound box, said attachment comprising a track arm adapted to extend over the record rotating means, means rotatable with the record rotating means for lifting said track arm at its inner extremity, a member carried by said track arm for engaging the lifting means, and means carried by the track arm 120 for timing the engagement of said member with the lifting means, said timing means comprising a device adapted to be set or placed along the track arm directly with reference to the tone grooves of the record so 125 130

that the engagement between the lifting means and said member carried by the track arm will take place substantially when the record has been played to the point indicated by said timing means.

3. In a repeating attachment for sound reproducing machines having means for rotating a disk record, a tone arm and a sound box, said attachment comprising a track arm adapted to extend over the record rotating means, means rotatable with the record rotating means for lifting said track arm at its inner extremity, a member carried by said track arm for engaging the lifting means, means carried by the track arm for timing the engagement of said member with the lifting means, said timing means comprising a device adapted to be set or placed along the track arm directly with reference to the tone grooves of the record so that the engagement between the lifting means and said member carried by the track arm will take place substantially when the record has been played to the point indicated by said timing means, and means movable with the tone arm for engaging said device.

4. In combination with a phonograph having a record rotating means for a disk record, a tone arm and sound box, a repeating attachment for causing the playing of the record to be repeated, and an electric circuit breaker embodied in said attachment and adapted to automatically open an electric circuit when the record has been played and repeated.

5. In combination with a phonograph having a record rotating means and a tone

arm, a repeating attachment for causing the playing of the record to be repeated once or a plurality of times, an electric circuit for a driving motor, and automatic means for causing the opening of the circuit after the record has been played the predetermined number of times.

6. In combination with a phonograph having a record rotating means, a tone arm and sound box, a repeating attachment for causing the playing of the record to be repeated, a brake lever for the record rotating means employed in conjunction therewith, an electric circuit for a driving motor, said circuit being connected to said brake lever, and a contact member engaging the same and connected to the motor circuit, said brake lever and contact member opening the circuit at a predetermined point in the cycle of operation.

7. In combination with a phonograph having a record rotating means, a tone arm and sound box, a repeating attachment for causing the playing of the record to be repeated a selected number of times, an electric circuit for a driving motor, said repeating attachment comprising a brake lever and means whereby the circuit is broken by said brake lever after the record has been played the predetermined number of times.

In testimony whereof, I hereunto affix my signature in the presence of two witnesses. 70
